SPHYGMOMANOMETER CUFF

William A. Baum, Forest Hills, and Bernard M. Hanafin, Kew Gardens, N. Y., assignors to W. A. Baum Co., Inc., New York, N. Y., a corporation of New York.

Application April 24, 1948, Serial No. 23,108.

6 Claims. (Cl. 128—327)

1

This invention relates to an inflatable cuff particularly adapted for use in sphygmomanometer apparatus. The invention provides for the first time a relatively short-length wholly flexible cuff of the simple wrap-around type, without reinforcing means therein, without positive locking or fastening devices thereon, and wherein the retention of the improved cuff in proper position and relation on the subject's limb during blood pressure measurements is attained substantially entirely by an inherent self-locking action developed by the specially prepared surface of the cuff material in adjacent-layer frictional contact relation, and which self-locking action is progressively enhanced and ultimately fully attained by the inflation of the inflatable bag associated with the cuff.

In accordance with a preferred embodiment of our invention the cuff is formed of a strip of flexible material without reinforcing or stiffening means therein, with a pocket at one end for the support of an inflatable bag. The inflatable bag provides a measure of the arterial pressure when inflated to constrict the flow of blood in the artery, and at the same time fixes the strip upon the limb. The strip is of a length sufficient to permit it to be wrapped around human limbs once with an overlap of not more than one turn.

In place of the tucking of the free end of the strip under one side of the assembled and applied cuff as is customary with the wrap-around cuffs of the prior art which are wrapped many times around the limb, the cuff of our invention relies upon a self-locking action between the overlapped ends of the short strip which is developed upon inflation of the inflatable bag. In view of the curved section of the limb about which the cuff is applied the force of friction between the overlapping areas at the outer margin thereof, i. e. at the free end of the strip, is effective to retain the overlapping areas in contact despite the tangential stress between the two ends of the strip which arises when the bag is inflated.

The result is a cuff which requires neither the length of the early period sphygmomanometer cuffs, wrapped repeatedly about the limb, and finally tucked in or tied in place with tapes, nor the hooks, snaps or other fasteners of certain shorter length cuffs of later periods. The complete pliability and flexibility of the cuff of our invention, without stiffeners of metal or other material enables measurements to be made under conditions similar to those under which the clinical averages of blood pressure now widely accepted were determined with the old bandage-

2

style sphygmomanometer cuff consisting of an inflatable bag supported by a long strip of flexible material.

Our invention will now be more fully described in connection with the accompanying drawings in which:

Fig. 1 is a longitudinal sectional perspective view of a cuff according to our invention in extended or unwrapped condition;

Fig. 2 is an enlarged sectional view of the cuff of Fig. 1 as applied about the upper arm of a patient;

Fig. 3 is a perspective view of a modified form of cuff in which means are provided to apply to the overlapped ends of the cuff an auxiliary compressive stress independently of the inflation of the bag and independently of the orientation of the cuff upon the patient's limb;

Fig. 4 is a perspective view similar to that of Fig. 3 showing a further modification of our invention; and

Fig. 5 is a view in section along the line 5—5 of Fig. 4.

Referring to Fig. 1, the sphygmomanometer cuff of our invention includes an inflatable bag 10 supported by means of a limb-encircling band or strip generally indicated at 15. The band 15 may be made up of one or more pieces of flexible material which function to support the bag and to provide the frictional contact by which the entire cuff is retained in position on the patient's limb. In the cuff of Fig. 1 there is provided a strip 16 of flexible material, which may be a woven fabric or a plastic substitute therefor, of a length sufficient to encircle the largest limbs encountered in practice and to overlap itself by one complete turn around the limb, or less. For cuffs intended to be applied to human arms the effective diameter of the limb is about five and three-quarters inches, so that the total length of the strip need be only of the order of some two feet.

A pocket 18, suitable to contain the inflatable bag 10, is provided on one surface 11 of the strip, adjacent one end 17 thereof. The surface 11 will be referred to as the inner surface inasmuch as the cuff is applied to the patient with this surface adjacent the limb. The pocket 18 may be formed by sewing or otherwise affixing a piece of flexible material 22 to the strip 16, with suitable openings along the edges for insertion and removal of the bag and for flexible tubes which connect the bag with an inflating bulb and a measuring instrument such as a manometer (not shown). The pocket-forming patch 22 will have the width of the strip 16 and should preferably

be highly flexible and pliable so as to permit the bag 10 to adapt itself to the contour of the limb without unnecessary stresses which might distort the bag and falsify the relation between bag pressure and arterial pressure. The cuff is applied by wrapping about the limb beginning with the end 17 and with the pocket-forming patch 22 next the skin of the patient.

On the outer surface 12 of the strip 16 opposite the pocket 18 there is provided at the bag-supporting end 17 an area 24 of frictional material chosen to have, in conjunction with a related area 26 on the inner surface 11 at the free end 19 of the strip, a high coefficient of friction when the two areas are placed in overlapping relation. The areas 24 and 26 may consist simply of rubber-impregnated areas on the strip 16, or areas coated with a pressure-sensitive tacky adhesive material, or patches of a finely corrugated rubber sheeting may be used, or a woven fabric having a rough surface. The entire strip 16 may be made of rubber-impregnated material so that the areas 24 and 26 are coextensive, respectively, with the outer and inner surfaces of the strip, except in the latter case for the area covered by the pocket-forming patch 22.

The cuff is applied by wrapping about the limb, beginning with the bag-supporting end 17 until the outside end 19 has been brought down over the bag end 17 with the areas 24 and 26 in overlapping relation, both overlying the inflatable bag 10. In applying the cuff to the upper arm of a patient, the bag-supporting end is applied to the side of the arm next the body so that the brachial artery will come approximately at the midpoint of the circumferential length of the bag 10. This is shown in Fig. 2, which is a view in section through the upper arm of a patient with the cuff of Fig. 1 applied thereabout, looking toward the extremity of the arm. The bag 10 is shown partially inflated and the brachial artery 27 is partly compressed. With the cuff so applied the free end 19 of the strip overlies the top of the arm and is retained in contact with the underlying layer of the cuff by means of its own weight. The frictional areas, 24 on the outer surface of the strip at the bag-supporting end 17 and 26 on the inner surface of the strip at the free end 19, are shown in overlapping relation.

The force of friction available between the contacting layers of fabric at the end 19 by virtue of the normal stress provided by the weight of the strip material, when called into action to withstand the tangential force tending to separate the overlapping portions of the strip which is generated when inflation of the bag commences, provides at circumferential locations back of the end 19 a progressively increasing holding stress because of the curved section of the arm. This holding stress holds the outer layer down over the inner layer so that the expansive force of the bag, as inflation is continued, stresses the overlapped layers of the cuff ever more tightly together. Inflation of the bag may proceed until the flow of blood in the artery 27 is entirely shut off, so that the usual measurements of systolic pressure may be made.

In order to provide at the outer or free end of our wrap-around cuff an initial compressive stress which will hold the overlapped layers thereof together independently of the orientation of the cuff upon the patient's arm until inflation of the inflatable bag locks the overlapping portions together, we provide in a modified form of our invention an auxiliary stress perpendicular

to the surfaces of the strip, by means acting independently of the inflation of the inflatable bag. This auxiliary stress may be provided by means attached to the outside edge of the free end of the strip. These means are immediately operable regardless of the girth of the limb about which the cuff is applied, i. e. regardless of the amount of overlap between the two ends of the strip. No fittings, spaced at discrete intervals or otherwise 5 required on the inner, underlying end of the strip to cooperate with these means. A cuff of this modified type is shown in Fig. 3. The auxiliary stress at the outside margin of overlap, i. e. at the outermost edge of the free end of the strip, is provided in the cuff of Fig. 3 by means of an elastically distensible loop 40. The loop may be made of rubber. It is fastened at the free end 39 of the cuff of Fig. 3 and is of such length as to encircle the limb outside of the wrapped cuff, under tension, and to hook onto a button or similar protuberance 42 affixed to the outermost edge of the free end 39. The cuff of Fig. 3 is applied by wrapping about the limb, beginning with the bag-supporting end 37 until the free end 39 has been brought down over the bag end 37 with the frictional areas thereof in overlapping relation. The elastic loop 40 is then stretched, in the same direction in wrapping, once around the limb over the cuff, and secured to the button 42. The inflatable bag may then be inflated and the blood pressure measured in the usual way, the inflation of the bag increasing the pressure between the frictional areas which prevents separation of the ends of the cuff.

35 In place of the loop of rubber or elastic described in connection with Fig. 3 for provision of an auxiliary perpendicular stress independent of inflation of the bag, a pair of small flaps may be provided one at either side of the outer end of the cuff. A cuff of this type is shown in Fig. 4 where tuck-in flaps 46 are disposed at the outer end 49 of a limb-encircling band 50. The flaps 46 are tucked under the inflatable bag contained in a pocket on the underside of the band. Thus inflation of the bag stresses the two ends of the cuff against each other perpendicularly to their surface area and increases the available force of friction which holds them in place. A sectional view of the cuff of Fig. 4 is shown in Fig. 5 where the relation of the flaps 46 to the bag and to the two ends of the cuff is shown.

Our invention is not intended to be restricted to the details of construction illustrated and discussed herein nor to the specific materials mentioned. Alternative materials having the properties set forth may of course be used. Changes and modifications may be made in the construction herein described without departing from the scope of our invention as set forth in the appended claims.

60 We claim:

1. A pneumatically retained sphygmomanometer cuff comprising a strip of flexible material constructed to encircle a human limb with an area of overlap between the ends thereof, a pocket formed on one end of the said strip, an inflatable bag disposed within the said pocket, and a pair of tuck-in flaps disposed one at either side of the end of said strip remote from the said bag, whereby upon the wrapping of the said strip about a patient's limb beginning with the bag-supporting end thereof and upon tucking the said flaps under the overlapped inflatable bag, inflation of the said bag stresses the overlapped ends of the said strip together.

2. An inflatable cuff adapted for use with sphygmomanometer apparatus comprising a strip of flexible material of a length sufficient to encircle a human limb not more than twice, an area of a tacky adhesive material applied to one side of said strip at one end thereof, an area of a tacky adhesive material applied to the other side of the said strip at the other end thereof, and an inflatable bag supported adjacent one end of the strip on the side thereof opposite the adhesive area, whereby upon the wrapping of the said strip about a limb of a patient beginning with the bag-supporting end thereof and with the said bag adjacent the skin of the limb, the said adhesive areas are brought into overlapping frictional contact relation augmented upon inflation of the inflatable bag.

3. A self-retaining inflatable cuff of the short wrap-around type consisting of flexible elements and comprising a strip of flexible material, an inflatable bag supported adjacent one end of the strip, the said strip having a length permitting it to be wrapped around human arms above the elbow with an overlap of less than one turn, and flexible means applied to the end of the strip remote from the bag providing adhesion between the overlapped ends of the strip when so wrapped.

4. A self-retaining inflatable cuff of the short wrap-around type consisting of flexible elements and comprising a strip of flexible material at least the overlapping end portions of which are adhesive to themselves and an inflatable bag disposed adjacent one end of said strip, said strip having a length permitting it to be wrapped

about a human limb with an overlap of less than one turn, whereby upon the wrapping of said strip about a limb of a patient said strip will be retained in place upon said limb by adhesion between the overlapped ends of said strip.

5. A self-retaining inflatable cuff as defined in claim 4 in which the strip of flexible material is inherently non-adhesive and at least one of the surfaces of the end portions which contact on overlapping have adhesive material thereon.

6. A self-retaining inflatable cuff as defined in claim 4 having an elastically distensible loop affixed to the end of the strip remote from the inflatable bag and a loop-securing protuberance secured to the same end of the strip as the loop, whereby upon wrapping of said strip about a human limb beginning with the bag-supporting end and upon securing the loop around the limb over the strip and onto the protuberance the two ends of the strip are placed in overlapping position and retained in position by the loop.
